LASTING MACHINE

John T. Lancaster, Newton, Mass., assignor to
United Shoe Machinery Corporation, Paterson,
N. J., a corporation of New Jersey

Application November 25, 1935, Serial No. 51,395

30 Claims.

(Cl. 12—14)

This invention relates to lasting machines, and in some aspects more particularly to toe-end lasting means. The invention is herein illustrated as embodied in a lasting machine of the bed type.

In the manufacture of various kinds of shoes, it is the common practice to subject the upper to a pulling-over operation whereby it is tensioned or stretched lengthwise of the last and is also shaped in general conformity to the contour of the forepart of the last, and thereafter to present the shoe to a different machine for the toe-lasting operation. In the toe-lasting operation it is usually the practice, after removing 10 one or more of the pulling-over tacks, to subject the upper around the toe end of the last to repeated upwiping operations to conform it tightly to the contour of the last before laying its marginal portion around the toe end inwardly over an insole or other shoe bottom part herein-after frequently referred to generically as a "sole." The upwiping operation is usually performed by means of end-embracing wipers which are shaped to conform substantially to the contour of the toe-end of the last. While the use 20 of such wipers has, for the most part, proved to be satisfactory it has been found, under some conditions of work, particularly where the heightwise contour of the toe end of the last is such as to render it difficult for the wipers to apply effective upwiping pressure to the upper along the sides of the toe end, that the upper has not been conformed as tightly to the contour of the last in those locations as is desirable.

In view of the above, the present invention, in one important aspect has in view the provision, in combination with means for laying the marginal portion of an upper inwardly over a sole on a last, of improved means for conforming the upper tightly to the contour of the last along the opposite sides of the toe end prior to the overlaying operation. In the use of a machine of the type herein shown in which the shoe is held firmly in position for the lasting operation by a heel support, a toe rest and a holdown, the toe rest is utilized to clamp the shoe against the holdown and to press the upper into conformity to the contour of the top of the forepart of the last, and novel upwiping devices are provided for wiping the upper at the opposite sides of the toe end toward the edge of the shoe bottom and for holding it clamped against the lateral faces of the last during the overlaying operation. In the illustrated construction, the toe rest comprises a resilient pad which is shaped

approximately to conform to the contour of the top of the forepart of the shoe and is mounted on a holder which is controlled by a spring yieldable in response to the upward movement of an operating member, used as heretofore in machines of the type herein shown to elevate the toe rest. The upwiping devices comprise wiping members which are arranged to engage the upper along the sides of the toe end of the last substantially from the tip line forwardly to the 10 "corners" of the toe end and are connected to rods which are slidable vertically through guide sleeves pivotally connected for swinging movements about axes extending lengthwise of the shoe to the above-mentioned holder, the rods 15 being connected at their lower ends to arms pivotally connected to the operating member. Thus as the toe rest is pressed yieldingly against the shoe to clamp the shoe against the holdown it conforms the upper to the contour of the top 20 of the forepart of the last, and the wiping members engage and wipe heightwise of the last at the opposite sides of the toe end portions of the upper located nearer the edge of the last bottom than the portion engaged by the toe rest. 25 Preferably, and as herein shown, there is also provided means for adjusting the wiping members toward or from each other widthwise of the shoe by varying the initial positions of the above-mentioned arms, and means arranged to 30 engage and to swing the arms in directions to force the wiping members yieldingly against the upper substantially at the beginning of their upwiping movements and for holding them in 35 clamping relation to the upper during the overlaying operation.

For best results in the upper shaping or conforming operation it is desirable that the pressure of the toe rest be applied to the shoe in such manner as to avoid any danger of damage to the upper by excessive pressure of the toe rest on the upper in any location and that the wiping members in the upwiping operation move in paths substantially normal to the plane of the bottom of the forepart of the shoe in order 40 to conform the upper tightly and smoothly to the contour of the lateral faces of the last at the toe end. For the purpose in view, the toe rest upon which the wiping members are mounted for movements heightwise of the shoe 45 is so constructed as to adjust itself to each shoe about an axis extending laterally of the shoe and located substantially in the plane of the bottom of the forepart of the shoe. In the construction shown, the holder, to which the 50

guiding means or sleeves for the wiping members are pivotally connected, is supported by a member provided with an arcuate slot concentric with such axis and in which there are 5 mounted rolls carried by the holder. Thus the toe rest is permitted to adjust itself readily to each shoe in response to pressure of the shoe thereon and to position the wiping members for movements in paths substantially normal to the 10 plane of the bottom of the forepart of the shoe.

The above and other features of the invention, including various novel details of construction and combinations of parts, will now be 15 more particularly described by reference to the accompanying drawings and pointed out in the claims.

In the drawings,

Fig. 1 is a view in front elevation of a machine embodying the present invention;

Fig. 2 is a view in front elevation of the toe rest for clamping the shoe against the hold-down and the upwiping devices, on an enlarged scale, the parts being shown in the positions that they occupy at the end of the unwiping 25 operation;

Fig. 3 is a section on the line III—III of Fig. 2;

Fig. 4 is a section similar to Fig. 3, but showing the parts in the positions that they occupy 30 prior to the upwiping operation;

Fig. 5 is a section on the line V—V of Fig. 4;

Fig. 6 is a vertical section of certain parts shown in Fig. 4 in a plane at right angles to that of Fig. 4; and

Fig. 7 is a detail view illustrating the relative positions of the upwiping members and the shoe during the overlaying operation.

The invention is herein illustrated as applied to a bed lasting machine of a well-known type features of the general organization of 40 which are disclosed in various United States Letters Patent including especially Letters Patent No. 1,018,477, granted on February 27, 1912, and No. 1,373,482, granted on April 5, 1921, 45 both upon applications of Matthias Brock. Only such features of the general organization therefore as it is necessary to refer to for an understanding of the invention are herein shown and will be described in detail.

Machines of this type include heel lasting 50 mechanism and toe-lasting mechanism between which the shoe and last are supported at the heel end by a jack 10 and at the toe end by a toe post 12. The toe-lasting mechanism comprises a wiper head 14 which is adjustable in 55 various ways lengthwise and laterally of the shoe with provision for tipping movement to position the toe-embracing wipers 16 substantially parallel to the plane of the forepart of the shoe bottom, the wipers 16 being operated 60 by a hand lever 18 (Fig. 1). The wiper head 14 is carried by a support 20 which is guided for vertical movements in the frame 22 of the machine and is connected by a link 24 to a 65 treadle 26 whereby the operator is enabled to raise or lower the wipers as desired. The toe post 12 is supported by a member 28 which is adjustable vertically by means of a hand wheel 30. The heel lasting mechanism is carried by 70 a head 32 which is mounted for movement lengthwise of the shoe toward or from a definite operative position in which position it is locked by a latch 34, Fig. 1. The jack 10 is fast to a slide, not herein shown, which is movable, by 75 means of a hand wheel 36 and connections

therefrom to the slide, against the tension of a return spring, in a direction to draw the shoe firmly back into the end-embracing band 37 of the heel lasting mechanism, means (not shown) being provided for locking the hand wheel to hold the slide against return movement. Thereafter, the machine is started by movement of a knee lever 42, whereupon the heel band is closed about the heel end of the shoe and the member 28 and the toe post 12 are moved upwardly by the action of a cam 44 on a lever 46 pivotally connected to a slide 48 to which the member 28 is adjustably secured. The machine is also provided with a hold-down 38 which is swung forwardly and downwardly and is depressed by a treadle 40 into position to engage the bottom of the forepart of the shoe. The hold-down 38 is in many respects similar to the disclosure of Letters Patent No. 1,188,403, granted on June 27, 1916 upon an application 20 of L. M. Brown, and comprises a projection 50 on the forward end of an arm 52 and a hold-down finger 54 carried by a block 56 adjustably secured to a spindle 58 of a member (not shown) which is rotatably mounted in the forward end 25 of the arm 52 and is connected to a torsion spring against the resistance of which the finger 54 may move relatively to the projection 50 to adapt itself to the "spring" or lengthwise inclination of the bottom of the forepart of the 30 shoe being operated upon. The arm 52 is slidably movable lengthwise in a holder 60 supported on a vertical rod 62. This supporting means and its operating mechanism, in the machine herein shown, are of substantially the 35 same construction as means provided heretofore in machines of the illustrated type for supporting a hold-down member and for pressing the member upon the shoe bottom, as disclosed in United States Letters Patent No. 1,120,822, 40 granted on December 15, 1914, on an application of E. L. Keyes.

For purposes of this invention, there is mounted on the toe post 12 a toe-supporting device or toe rest which, as herein shown, comprises a holder 64 (Figs. 2, 3 and 4) having 45 mounted thereon a flexible resilient pad 66, preferably of rubber, for engaging the shoe, the pad being shaped approximately to conform to the top of the forepart of the shoe. The holder 64 is mounted on a support 68 which has a depending hollow stem 70 (Figs. 3 and 4) slidably mounted in a vertical central bore in the post 12. The post 12 is freely slideable vertically 50 through a guide sleeve 72 (Fig. 1) on a bar 74 that is slideable horizontally on the under side of the toe lasting head, as usual, and as appears more in detail in said prior Patent No. 1,373,482. Threaded into the lower end of the toe post 12 is an adjusting screw 76 which rests on the member 28 and by means of which the initial 55 heightwise position of the toe rest may be varied. The toe rest is pressed firmly against the shoe in the upward movement of the supporting member 28 and the post 12 by a spring 78 (Figs. 3 and 4) engaging the lower end face of the hollow stem 70 within the central bore in the post 12. To limit movement of the toe rest in one direction when there is no shoe in the machine there is provided a pin 80 which extends through vertical 60 slots 82 in the hollow stem 70 and engages the post 12 at the upper ends of vertical slots 84 in the post (Fig. 6). The pin 80 extends also through apertures in a sleeve 86 which surrounds the upper end portion of the toe post 12 65 70 75 75

and is slidably vertically thereon. A spring 88 within the depending hollow stem 70 of the support 68 engages the pin 80. Pivotally connected to the post 12, one on each side of the shoe, are arms 90, the upper ends of which are pivotally connected guide blocks 92 for rods 94. The rods 94 extend upwardly through guide sleeves 96 which are pivotally connected at 98 for swinging movements about axes extending lengthwise of the shoe to laterally extending ears 100 on the holder 64, and pivotally connected to the upper ends of the rods 94 are wiping members 102 for engaging the upper at the sides of the last above the pad 66 and for wiping the upper upwardly toward the edge of the sole. The members 102, which are preferably made of rubber, are secured to blocks 104 pivotally connected to the upper ends of the rods 94. As shown in Figs. 1 and 2, the wiping members 102 extend lengthwise of the shoe substantially from the tip line (if the shoe has a toe tip) forwardly to the "corners" of the toe end and have plane upper surfaces 106 which are substantially parallel to the axes 98 of the guide sleeves 96. Fast to each rod 94 and arranged to engage the top and bottom faces of the guide blocks 92 are collars 108. The arms 90 have downwardly extending portions 110 provided with recesses to receive springs 112 the opposite ends of which engage the toe post 12. The springs 112 tend to swing the arms 90 inwardly toward each other, their inward movements being limited by screws 114 carried by the arms and engaging the toe post 12. It will be readily seen that as the arms 90 are swung inwardly toward each other the rods 94 and the guide sleeves 96 are swung about the axes 98 of the guide sleeves in directions to move the wiping members 102 outwardly away from each other, and that by adjusting the screws 114 the initially spaced apart positions of the wiping members may be varied. Preferably the wiping members 102 will be adjusted laterally of the last so as to engage the upper initially at the opposite sides of the last just above the pad 66.

By reference to Fig. 4 it will be seen that the sleeve 86 is cut away to permit the arms 90 to swing inwardly toward each other. Formed upon the sleeve 86 are cam surfaces 116 which are arranged to be engaged by the rounded upper ends of the arms 90 substantially at the beginning of the upward movement of the toe post 12. As the arms 90 are moved upwardly to impart to the wiping members 102 through the collars 108 and rods 94 their upwiping movements they are also swung outwardly by the action of the cams 116 on their rounded upper ends. Outward swinging movement of the arms 90 causes the wiping members 102 to be pressed more firmly against the shoe, the construction being such that in the upward movement of the toe post 12, when the spring 78 is compressed in response to the pressure of the shoe on the pad 66, the arms 90 are moved into engagement with the cams 116 on the sleeve 86 which is held against movement relatively to the support 68 by the action of the spring 88 on the pin 80 carried by the sleeve. Thereafter in response to resistance of the shoe to the pressure applied by the wiping members 102 the spring 88 yields and the sleeve 86 is moved upwardly with the arms 90, the spring 88 acting then to hold the arms 90 in such positions as to prevent any relaxing of the pressure of the wiping members 102 on the upper.

In order that the wiping members 102 will move upwardly in paths substantially normal to the plane of the bottom of the forepart of the shoe, the toe rest, to which the guide sleeves 96 for the rods 94 of the wiping members are pivotally connected, is so constructed as to permit it to adjust itself to each shoe about an axis extending laterally of the shoe and located substantially in the plane of the bottom of the forepart of the shoe. As herein shown, the support 68 has an arcuate slot 118 (Fig. 2) formed therein concentric with such axis and in which there are mounted rolls 120 carried by the holder 64 of the toe rest. The holder 64 has a pair of downwardly extending flanges 122 which engage the opposite side faces of the support 68, and supported by these flanges are pins 124 upon which the rolls 120 are rotatably mounted. Set screws 126 threaded into one of the flanges and engaging the pins 124 act to hold the pins 20 against endwise movement. The holder 64 is thus mounted on the support 68 to turn freely about an axis extending laterally of the shoe and located substantially in the plane of the bottom of the forepart of the shoe to adjust 25 itself to each shoe. As the holder 64 thus adjusts itself to the shoe the guide sleeves 96 for the rods 94 are also adjusted about the same axis to position the rods 94 and the wiping members 102 for upward movements in paths substantially 30 normal to the plane of the bottom of the forepart of the shoe. To permit the rods 94 to be thus adjusted relatively to the guide blocks 92, these blocks are provided with elongated slots 128 (Figs. 2 and 5) through which the rods 94 35 extend, the top and bottom faces of the blocks 92 being preferably also concentric with the axis about which the holder 64 is adjustable.

In the operation of the machine, briefly summarized, after a shoe is positioned at the desired height upon the jack 10 and the toe rest, the heel-end-lasting head 32 is moved to the left into operative position and the hand wheel 36 is operated to force the shoe rearwardly into the heel band 37. The holdown 38 is then 40 swung forwardly and downwardly by the operator and is depressed by the treadle 40 into position to engage the bottom of the forepart of the shoe. It will be understood that as the shoe is placed on the toe rest by the operator 50 the toe rest will adjust itself to the shoe about an axis extending laterally of the shoe and located substantially in the plane of the bottom of the forepart of the shoe and the wiping members 102 will thus be positioned for upward 55 movements in paths substantially normal to that plane. Thereafter the machine is started by movement of the knee lever 42, whereupon the heel band is closed about the heel end of the shoe and the toe post 12 is elevated by 60 upward movement of the member 28 and slide 48 in response to the action of the cam 44 on the arm 46. In response to the upward movement of the toe post the shoe is clamped yielding 65 against the holdown 38 and the wiping members 102 are carried nearly to the edge of the shoe bottom. As the shoe is thus clamped yielding against the holdown the upper at the top of the forepart is pressed into conformity to the contour of the last by the pad 66 and portions of the upper located nearer the edge of the shoe bottom than the portions engaged by the pad are conformed tightly to the contour of the last by the wiping members 102. Thereafter, with the upper held tightly conformed to 70

75 75

the contour of the top and sides of the toe end of the last by the pad 66 and wiping members 102, the wipers 16 are raised by the treadle 26 substantially to the edge of the sole and are advanced and closed above the wipers 102 until their inner edges are close to the upper. The operator then with the fingers of his right hand or with a suitable spreading tool, spreads the margin of the upper at the extreme toe end 10 of the last outwardly over the wipers 16 and while holding the margin of the upper thus pressed against the wipers further raises the wipers, thereby tensioning this portion of the upper heightwise of the last, and by means of 15 the hand lever 18 advances and closes the wipers to wipe the marginal portion of the upper around the toe end and along the sides of the toe end inwardly over the sole. It will be understood that by depressing the right-hand portion 20 of the treadle 26 the operator may increase the pressure of the wipers 16 on the upper during their inward movements and that after the wipers have been advanced and closed, they may be retracted and again advanced and closed to 25 wipe the marginal portion of the upper over the sole a second time. It will be understood also that prior to the second overwiping operation the wipers 16 may be retracted far enough to permit the operator to trim the lining and 30 box toe back nearly to the edge of the sole and to apply cement to the margin of the upper and to the sole to hold the upper in lasted position after it has been again wiped inwardly over the sole, or the marginal portion of the upper 35 may be fastened in lasted position by tacks at the end of the overlaying operation. The different parts of the lasting mechanism are then returned to their starting positions and the shoe removed from the machine.

40 While the invention is illustrated by reference to the manufacture of shoes of that type in which the margin of the upper for its entire width is lasted in substantially parallel relation to the outer or bottom face of a sole it will be 45 understood that the invention is not limited to the manufacture of shoes of that particular type.

Having described my invention, what I claim as new and desire to secure by Letters Patent 50 of the United States is:

1. In a lasting machine, the combination with means for laying the marginal portion of an upper around the toe end of a last inwardly over the bottom of the last, of a toe rest for 55 pressing the upper at the top of the forepart yieldingly against the last, a device movable heightwise of the last for operating said toe rest, and upwiping devices for wiping the upper at the opposite sides of the toe end toward the 60 bottom edge of the last in response to further movement of said last-named device heightwise of the last after the toe rest has been pressed yieldingly against the upper.

2. In a lasting machine, the combination with 65 means for laying the marginal portion of an upper around the toe end of a last inwardly over the bottom of the last, of a toe rest for engaging the upper opposite the top of the forepart of the last, operating means movable heightwise of the last for moving said toe rest 70 yieldingly to press the upper against the last, and upwiping devices controlled by said operating means for wiping the upper at the opposite sides of the toe end toward the edge of the last 75 bottom.

3. In a lasting machine, the combination with means for laying the marginal portion of an upper around the toe end of a last inwardly over the bottom of the last, of a toe rest for engaging the upper opposite the top of the forepart of the last, wipers for engaging the upper at the opposite sides of the toe end of the last, an operating member movable heightwise of the last, a spring for operating said toe rest to press the upper against the last by the movement of 10 said operating member, and connections between said operating member and the wipers for moving them heightwise of the last to wipe the upper toward the edge of the last bottom. 15

4. In a lasting machine, the combination with means for laying the marginal portion of an upper around the toe end of a last inwardly over the bottom of the last, of a toe rest for engaging the upper opposite the top of the forepart of the last, upwiping devices for wiping the upper at 20 the opposite sides of the toe and heightwise of the last, operating means for moving said toe rest to press the upper yieldingly against the last and for imparting to said upwiping devices their movements heightwise of the last, and 25 means for forcing said upwiping devices yieldingly against the upper substantially at the beginning of their upwiping movement.

5. In a lasting machine, the combination with means for laying the marginal portion of an upper around the toe end of a last inwardly over the bottom of the last, of a toe rest, wipers for engaging the upper at the opposite sides of the toe end of the last, an operating member movable heightwise of the last, a spring for operating said toe rest by the movement of said operating member to press the upper yieldingly against the last, and connections between said operating member and the wipers for moving them heightwise of the last to wipe the upper 40 toward the bottom edge of the last, said connections being adjustable to vary the positions of the wipers relatively to each other widthwise of the last. 45

6. In a lasting machine, the combination with means for laying the marginal portion of an upper around the toe end of a last inwardly over the bottom of the last, of a toe rest, wipers for engaging the upper at the opposite sides of the toe end of the last, an operating member movable heightwise of the last, a spring for operating said toe rest by the movement of said operating member to press the upper yieldingly against the last, connections between said operating member and the wipers for moving them heightwise of the last to wipe the upper toward the edge of the last bottom, said connections being adjustable to vary the positions of the wipers relatively to each other widthwise of the last, and means arranged to act through said 50 connections to force the wipers yieldingly against the upper substantially at the beginning of their movements heightwise of the last. 55

7. In a lasting machine, the combination with means for laying the marginal portion of an upper around the toe end of a last inwardly over a sole, of a toe rest, wipers for engaging the upper at the opposite sides of the toe end of the last, an operating member movable heightwise of the last, a spring for operating said toe 65 rest to press the upper against the last by the movement of said operating member, connections between said operating member and the wipers for moving them heightwise of the last to upwipe the upper, and means arranged to act 70

75

through said connections to force the wipers yieldingly against the upper substantially at the beginning of the movement of said operating member heightwise of the last.

5 8. In a lasting machine, the combination with means for laying the marginal portion of an upper around the toe end of a last inwardly over a sole, of a toe rest, wipers for engaging the upper at the opposite sides of the toe end of the last, an operating member movable heightwise of the last, a spring for operating said toe rest to press the upper against the last by the movement of said operating member, connections between said operating member and the 10 wipers for moving them heightwise of the last to upwipe the upper including arms pivotally connected to said operating member, rods connecting said arms and the wipers, guide sleeves for said rods pivotally connected to said toe rest, 15 and means arranged to act on said arms substantially at the beginning of the movement of said operating member heightwise of the last to swing them in directions to force said wipers yieldingly against the upper.

20 9. In a lasting machine, the combination with means for laying the marginal portion of the toe end of an upper inwardly over the bottom of a last, of a toe rest, wipers for engaging the upper at the opposite sides of the toe end of the last, an operating member movable heightwise of the last, a spring for operating said toe rest by the movement of said operating member to press the upper yieldingly against the last, connections between said operating member and the wipers for 25 moving them heightwise of the last to wipe the upper toward the edge of the last bottom including arms pivotally connected to said operating member, and cam means arranged to act on said arms to swing them in directions to force said wipers against the upper in their upwiping movements.

30 40

10. In a lasting machine, the combination with means for laying the marginal portion of the toe end of an upper inwardly over the bottom of a last, of a toe rest, wipers for engaging the upper at the opposite sides of the toe end of the last, an operating member movable heightwise of the last, a spring for operating said toe rest by the movement of said operating member to press the upper yieldingly against the last, connections between said operating member and the wipers for moving them heightwise of the last to wipe the upper toward the edge of the last bottom including arms pivotally connected to said operating member, cam means arranged to act on said arms to swing them in directions to force said wipers against the upper substantially at the beginning of their upwiping movements, and a spring for controlling said cam means, said spring being yieldable in response to resistance of the shoe to the pressure applied by said wipers.

45 55 60 65 70 75

11. In a lasting machine, the combination with means for laying the marginal portion of an upper around the toe end of a last inwardly over the bottom of the last, of a toe rest, wipers for engaging the upper at the opposite sides of the toe end of the last, an operating member movable heightwise of the last, a spring for operating said toe rest by the movement of said operating member to press the upper yieldingly against the last, connections between said operating member and the wipers for moving them heightwise of the last to wipe the upper toward the bottom edge of the last including a pair of arms

5 10 15 20 25 30 35 40 45 50 55 60 65 70 75

pivots connected to said operating member, a sleeve on said operating member and relatively to which said operating member is movable, and a pair of cam surfaces on said sleeve arranged to act on said arms to swing them in directions to force said wipers against the upper substantially at the beginning of the movement of said operating member heightwise of the last.

12. In a lasting machine, the combination with means for laying the marginal portion of an upper around the toe end of a shoe inwardly over a sole, of a holddown for engaging the bottom face of the sole, a toe rest, a support for said toe rest movable heightwise of the shoe and relatively to which said toe rest is mounted for self-adjustment to each shoe about an axis extending laterally of the shoe, upwiping devices mounted on said toe rest for wiping the upper heightwise of the shoe at the opposite sides of the toe end of the shoe, and means for moving said support and toe rest yieldingly to press the shoe against said holddown and for operating said upwiping devices.

13. In a lasting machine, the combination with means for laying the marginal portion of an upper around the toe end of a shoe inwardly over a sole, of a holddown for engaging the bottom face of the sole, a toe rest, a support for said toe rest movable heightwise of the shoe and relatively to which said toe rest is mounted for self-adjustment to each shoe about an axis extending laterally of the shoe, wipers adjustable with said toe rest for engaging the upper at the opposite sides of the toe end of the shoe, an operating member movable heightwise of the shoe, a spring for operating said support and toe rest to press the shoe yieldingly against the holddown by the movement of said operating member, and connections between said operating member and the wipers for moving them heightwise of the shoe to upwipe the upper.

14. In a lasting machine, end-embracing wipers for laying the marginal portion of an upper around the toe end of a shoe inwardly over a sole, a holddown for engaging the bottom face of the sole to determine the position of the shoe heightwise relatively to said wipers, a toe rest for engaging the shoe at the top of the forepart to clamp the shoe against said holddown, and upwiping devices mounted independently of each other for engaging the upper at the opposite sides of the toe end, said devices being movable heightwise of the shoe to wipe the upper toward the bottom edge of the sole prior to the overlaying operation.

15. In a lasting machine, end-embracing wipers for laying the marginal portion of an upper around the toe end of a shoe inwardly over a sole, a holddown for engaging the bottom face of the sole to determine the position of the shoe heightwise relatively to said wipers, a toe rest for engaging the top of the forepart of the shoe to clamp the shoe against said holddown, upwiping devices independently mounted at the opposite sides of the shoe and movable heightwise of the shoe to wipe the upper in locations forwardly of the tip line toward the bottom edge of the sole, means for imparting to said devices their movements heightwise of the shoe, and means for forcing said devices yieldingly against the upper substantially at the beginning of their upwiping movements.

16. In a lasting machine, end-embracing wipers for laying the marginal portion of an upper around the toe end of a shoe inwardly over a

sole, a holdown for engaging the bottom face of the sole to determine the position of the shoe heightwise relatively to said wipers, a toe rest for engaging the shoe at the top of the forepart to 5 clamp the shoe against said holdown, upwiping devices movable heightwise of the shoe to wipe the upper at the sides of the toe end toward the bottom edge of the sole, and a single means for operating said toe rest to clamp the shoe against 10 the holdown and for imparting to said devices their movements heightwise of the shoe.

17. In a lasting machine, end-embracing wipers for laying the marginal portion of an upper around the toe end of a shoe inwardly over a sole, 15 a holdown for engaging the bottom face of the sole to determine the position of the shoe heightwise relatively to said wipers, a toe rest for engaging the shoe at the top of the forepart to clamp the shoe against said holdown, upwiping 20 devices independently mounted at the opposite sides of the shoe for wiping the upper along the sides of the toe end of the shoe heightwise of the shoe, and cam-controlled means movable heightwise of the shoe for pressing the toe rest 25 yieldingly against the shoe and for operating the unwiping devices.

18. In a lasting machine, the combination with 30 end-embracing wipers for laying the marginal portion of an upper inwardly over a sole around the toe end of a shoe, of devices movable heightwise of the shoe for wiping the upper at the opposite sides of the toe end toward the bottom edge of the shoe, and a toe rest on which said devices are mounted, said toe rest being arranged 35 to engage the top of the forepart of the shoe and being movable in response to pressure of the shoe upon it about an axis extending laterally of the shoe and located substantially in the plane of the bottom of the forepart of the shoe to position 40 said devices for movement in paths substantially normal to said plane.

19. In a lasting machine, the combination with 45 end-embracing wipers for laying the marginal portion of an upper inwardly over a sole around the toe end of a shoe, and a holdown for engaging the bottom face of the sole to determine the position of the shoe heightwise relatively to said wipers, of upwiping devices for 50 wiping the upper at the opposite sides of the toe end of the shoe toward the bottom edge of the sole, a toe rest on which said devices are mounted, said toe rest being mounted for adjustment to each shoe about an axis extending laterally of the shoe, and means for pressing 55 said toe rest yieldingly against the shoe to clamp the shoe against said holdown and for operating said upwiping devices.

20. In a lasting machine, the combination with 60 end-embracing wipers for laying the marginal portion of an upper around the toe end of a shoe inwardly over a sole, of a toe rest for engaging the shoe at the top of the forepart, upwiping devices mounted on said toe rest for movement heightwise of the shoe to wipe 65 the upper at the sides of the toe end toward the bottom edge of the sole, and curved guiding means on which said toe rest is mounted for adjustment to each shoe about an axis extending laterally of the shoe to cause said upwiping devices to be positioned by said toe rest for movement 70 in paths substantially normal to the plane of the bottom of the forepart of the shoe.

21. In a lasting machine, the combination with 75 end-embracing wipers for laying the marginal portion of an upper around the toe end

of a shoe inwardly over a sole, of a toe rest for engaging the shoe at the top of the forepart, upwiping devices mounted on said toe rest for movement heightwise of the shoe to wipe the upper at the sides of the toe end toward the bottom edge of the sole, a member for supporting said toe rest provided with arcuate slots concentric with an axis extending laterally of the shoe and located substantially in the plane of the bottom of the forepart of the shoe, and rolls 10 carried by said toe rest and extending through said arcuate slots to permit movement of said toe rest about said axis in response to pressure of the shoe thereon.

22. In a lasting machine, the combination 15 with means for laying the marginal portion of an upper around the toe end inwardly over an insole on a last, of means for conforming the upper tightly to the contour of the toe end of the last comprising a resilient pad for pressing 20 the upper against the last at the top of the forepart, members arranged to engage and to wipe heightwise of the last portions of the upper located nearer the edge of the last bottom than the portion engaged by said pressing pad, means 25 for pressing said pad against the upper and for imparting to said members their wiping movements, and means for increasing the pressure of said members on the upper substantially at the beginning of their wiping movements. 30

23. In a lasting machine, the combination with means for laying the marginal portion of an upper around the toe end inwardly over an insole on a last, of means for conforming the upper tightly to the contour of the toe end of the last comprising a resilient pad for pressing 35 the upper against the last at the top of the forepart, members arranged to engage and to wipe heightwise of the last portions of the upper located nearer the edge of the last bottom 40 than the portion engaged by said pressing pad, mechanism for pressing said pad against the upper and for imparting to said members their wiping movements including a spring yieldable 45 in response to pressure of the last on said pad, and mechanism operative in response to the yielding of said spring for increasing the pressure of said wiping members on the upper. 50

24. In a lasting machine, the combination with means for laying the marginal portion of an upper around the toe end inwardly over an insole on a last, of means for conforming the upper tightly to the contour of the toe end of the last comprising a resilient pad for pressing 55 the upper into conformity to the contour of the top of the forepart of the last, wipers for engaging the upper along the sides of the toe end of the last at the opposite ends of said pad, means for moving said wipers heightwise of the last to wipe the upper toward the bottom face of 60 the insole, and a spring arranged to be tensioned in response to the movement of said last-named means for pressing the pad against the upper.

25. In a lasting machine, the combination 65 with means for laying the marginal portion of an upper around the toe end inwardly over an insole on a last, of means for conforming the upper tightly to the contour of the toe end of the last prior to the overlaying operation, 70 said conforming means comprising a resilient pad for pressing the upper against the last at the top of the forepart, a holder for said pad, a support for said holder relatively to which said holder is mounted for self-adjustment to 75

each shoe about an axis extending laterally of the shoe and located substantially in the plane of the bottom of the forepart of the shoe, and members adjustable relatively to each shoe with 5 said holder and arranged to engage and to wipe heightwise of the shoe at the opposite sides of the toe end portions of the upper located nearer the edge of the shoe bottom than the portion engaged by said pressing pad.

10 26. In a lasting machine, the combination with means for laying the marginal portion of an upper around the toe end inwardly over an insole on a last, of members for engaging the upper along the opposite sides of the toe end 15 of the last forwardly of the tip line and movable heightwise of the last to conform the upper tightly to the contour of the last by frictional contact therewith prior to the overlaying operation, said members being adjustable 20 relatively to each shoe about an axis extending laterally of the shoe and located substantially in the plane of the bottom of the forepart of the shoe.

27. In a lasting machine, the combination 25 with means for laying the marginal portion of an upper around the toe end inwardly over an insole on a last, of members for engaging the upper along the opposite sides of the toe end of the last forwardly of the tip line and movable 30 heightwise of the last to conform the upper tightly to the contour of the last by frictional contact therewith, and guiding means for said members adjustable relatively to each shoe about an axis extending laterally of the shoe 35 to position said members for movement relatively to the shoe in paths substantially normal to the plane of the bottom of the forepart of the shoe.

28. In a lasting machine, the combination

with means for laying the marginal portion of an upper around the toe end inwardly over an insole on a last, of wipers for wiping the upper heightwise of the shoe at the opposite sides of the toe end, and guiding means for said wipers adjustable relatively to each shoe about an axis 5 extending laterally of the shoe and located substantially in the plane of the bottom of the forepart of the shoe.

29. In a lasting machine, the combination 10 with means for laying the marginal portion of an upper around the toe end inwardly over an insole on a last, of wipers for wiping the upper heightwise of the shoe at the opposite sides of the toe end, guiding means for the wipers, and 15 supporting means for said guiding means arranged by engagement with the top of the forepart of each shoe to adjust said guiding means about an axis so located as to cause said wipers to move relatively to the shoe in paths substantially normal to the plane of the bottom of the forepart of the shoe.

30. In a lasting machine, end-embracing wipers for laying the marginal portion of an upper around the toe end inwardly over an insole on a last, a holdown arranged to position the shoe relatively to said end-embracing wipers by engagement with the bottom face of the insole, additional wipers movable heightwise of the shoe in wiping engagement with the upper 25 at the opposite sides of the toe end prior to the operation of said end-embracing wipers, and means arranged by engagement with the top of the forepart of the shoe to position said last-named wipers for movement relatively to the 30 shoe in paths substantially normal to the plane of the bottom of the forepart of the shoe.

JOHN T. LANCASTER.
